UNITED STATES PATENT OFFICE

ARTHUR A. CONSTABEL, OF NORRISTOWN, PENNSYLVANIA, ASSIGNOR TO THE BAILEY,
BANKS & BIDDLE COMPANY, OF PHILADELPHIA, PENNSYLVANIA, A CORPORATION
OF PENNSYLVANIA

DESIGN FOR A RING

Application filed January 24, 1930. Serial No. 34,274. Term of patent 7 years.

To all whom it may concern:

Be it known that I, ARTHUR A. CONSTABEL, a citizen of the United States, residing at Norristown, in the county of Montgomery and State of Pennsylvania, have invented a new, original, and ornamental Design for Rings, of which the following is a specification, reference being had to the accompanying drawings, forming part thereof.

In these illustrations Fig. I is a side plan view;

Fig. II is a top plan view; and,

Figs. III and IV are opposite edge views respectively of a ring showing my new design.

I claim:

The ornamental design for a ring, as shown.

ARTHUR A. CONSTABEL.
